(57) **CLAIM**

I claim the ornamental design for a carrier for bottles, cans, beverages, food containers, or the like, as shown and described.

DESCRIPTION

FIG. 1 is a perspective view of the first embodiment of a carrier for bottles, cans, beverages, food containers, or the like;

FIG. 2 is a perspective view thereof from a different angle;

FIG. 3 is a front elevation view thereof;

FIG. 4 is a rear elevation view thereof;

FIG. 5 is a right side elevation view thereof;

FIG. 6 is a left side elevation view thereof;

FIG. 7 top view thereof;

FIG. 8 is a bottom view thereof;

FIG. 9 is a perspective view of a second embodiment of a carrier for bottles, cans, beverages, food containers, or the like;

FIG. 10 is a perspective view thereof from a different angle;

FIG. 11 is a front elevation view thereof;

FIG. 12 is a rear elevation view thereof;

FIG. 13 is a right side elevation view thereof;

FIG. 14 is a left side elevation view thereof;

FIG. 15 is a top view thereof; and,

FIG. 16 is a bottom view thereof.

Specific features shown in broken lines do not form any part of or otherwise limit the claimed design.
